UNITED STATES PATENT OFFICE.

ISAAC E. PALMER, OF MIDDLETOWN, CONNECTICUT.

DESIGN FOR A HAMMOCK-BODY.

SPECIFICATION forming part of Design No. 36,885, dated April 19, 1904.

Application filed March 16, 1904. Serial No. 198,515. Term of patent 14 years.

To all whom it may concern:

Be it known that I, ISAAC E. PALMER, a citizen of the United States, and a resident of Middletown, in the county of Middlesex and State of Connecticut, have invented a new, original, and ornamental Design for a Hammock-Body, of which the following is a specification.

The accompanying drawing illustrates a section of hammock-body embodying my new,

original, and ornamental design, such illustration rendering the same clear without further description.

What I claim is—

The ornamental design for a hammock-body substantially as herein illustrated.

ISAAC E. PALMER.
